UNITED STATES PATENT OFFICE.

FREDERICK B. MALLORY, OF PORTLAND, OREGON.

DESIGN FOR A BLOCK SIDE.

42,487.

Specification for Design.

Patented May 7, 1912.

Application filed January 31, 1912. Serial No. 674,618. Term of patent 7 years.

To all whom it may concern:

Be it known that I, FREDERICK B. MALLORY, a citizen of the United States, residing at Portland, in the county of Multnomah and State of Oregon, have invented a new, original, and ornamental Design for Block Sides, of which the following is a specification, reference being had to the accompanying drawing, forming part thereof, in which—

Figure 1 is a front view of my invention and Fig. 2 is a side elevation of same.

Like characters of reference indicate like parts in the figures of the drawing, in which—

The numeral 1 indicates the body portion

of my design; the numeral 2 indicates shank members curving outward from said body portion and terminating in lugs 3. The shank members 2, are approximately circular in section.

I claim:

The ornamental design for a block-side as shown and described.

In testimony that I claim the foregoing as my own, I hereunto affix my signature in the presence of two subscribing witnesses.

F. B. MALLORY.

Witnesses:

M. A. KELLIHER,
E. DUFFY.
